John H. Doran
His Attorney.

UNITED STATES PATENT OFFICE.

JOHN H. DORAN, OF SCHENECTADY, NEW YORK, ASSIGNOR TO GENERAL ELECTRIC COMPANY, A CORPORATION OF NEW YORK.

ELASTIC-FLUID TURBINE.

Application filed June 21, 1926. Serial No. 117,293.

The present invention relates to elastic fluid turbines, and especially to rotors for such turbines.

At the low pressure end of a turbine rotor 5 for a large machine, the buckets become quite long and it is well known in connection with bucket rows having buckets of considerable length to provide circumferentially-extending tie wires between the inner and outer 10 ends of the buckets to strengthen them and increase the stiffness of the buckets. It is desirable from the standpoint of strengthening the bucket row that such tie wires extend continuously around the wheel, that is, that they 15 be in the form of continuous unbroken rings. However, generally they have been made in sections in order to avoid the stresses which would be set up in a continuous tie wire when the turbine is in operation. In this connection, it will be appreciated that when a turbine rotor is running, the buckets stretch in a 20 radial direction due to centrifugal force, and this tends to increase the diameter. This means, if a tie wire is continuous, that it must 25 stretch also so that in the case of an ordinary tie wire, if made continuous, stresses of an excessive value may be set up in it.

The object of my present invention is to provide an improved tie wire which may be 30 continuous and which is capable of stretching a limited amount without having stresses of an excessive value set up in it, and for a consideration of what I believe to be novel and my invention, attention is directed to the accompanying description and the claims appended thereon.

In the drawing, Fig. 1 is a side view of a portion of a turbine rotor, the buckets of which are provided with a tie wire embodying 40 my invention, and Fig. 2 is a radial sectional view.

Referring to the drawing, 1 indicates a turbine shaft, 2 a rotor thereon, 3 a row of buckets carried by the rotor, and 4 a sectional bucket cover for the buckets. Intermediate 45 between their ends, the buckets are provided with tie wires 5 permanently fastened in notches 6 in the edges of the buckets.

Now, according to my invention, I form

the tie wire of one continuous piece and between buckets I provide expansible bends or kinks in the tie wire, as is indicated at 7. By this arrangement, I provide a tie wire which is sufficiently stiff between buckets to hold the buckets in a wholly satisfactory manner, but which at the same time is capable of straightening out slightly or stretching so as to take care of an increase in diameter due to the buckets stretching, without subjecting the tie wire to excessive stresses. It will be appreciated of course, that the increases met with are of small value so that the actual amount the tie wire must straighten out or stretch is not great. The kink or bend in the tie wire, therefore, need not be large.

By my invention, I am enabled to provide tie wires which are continuous around the bucket ring and which avoid the difficulties met with heretofore in the use of continuous tie wires.

What I claim as new and desire to secure by Letters Patent of the United States is:

1. The combination with a turbine rotor having a row of buckets, of a tie wire for the buckets, said tie wire being in one continuous piece secured to the buckets and having kinks along its length which lie between the buckets and are expansible to permit the wire to be stretched.

2. The combination with a turbine rotor having an annular row of buckets, of a tie wire for the buckets in the form of a continuous ring permanently fastened in the edges of the buckets, the edges of the buckets being notched to receive the wire and said wire having kinks along its length which lie between the buckets.

3. The combination with a turbine rotor having a row of buckets, of a tie wire extending along the row and secured to the buckets, said wire having expansible bends between the buckets which permit the wire to be stretched without setting up in it stresses of excessively high value.

In witness whereof, I have hereunto set my hand this 19th day of June, 1926.

JOHN H. DORAN.
